UNITED STATES PATENT OFFICE.

HOWARD J. GORGAS, OF READING, PENNSYLVANIA, ASSIGNOR TO VANITY FAIR
SILK MILLS, OF READING, PENNSYLVANIA, A CORPORATION OF PENNSYLVANIA.

DESIGN FOR A TEXTILE FABRIC.

61,092.

Specification for Design. Patented June 20, 1922.

Application filed May 12, 1921. Serial No. 469,060. Term of patent 14 years.

To all whom it may concern:

Be it known that I, HOWARD J. GORGAS, a citizen of the United States, residing at Reading, in the county of Berks and State of Pennsylvania, have invented a new, original, and ornamental Design for a Textile Fabric, of which the following is a specification, reference being had to the accompanying drawing, forming a part thereof.

The figure shown is a piece of textile fabric illustrating my new design.

I claim:

The ornamental design for a textile fabric as shown.

HOWARD J. GORGAS.
